(57) **CLAIM**

The ornamental design for a three dimensional printer, as
shown and described.

DESCRIPTION

FIG. 1 is a front perspective view of a first embodiment of
a three dimensional printer showing our new design;

FIG. 2 is a left side perspective view showing the design for
the three dimensional printer of FIG. 1;

FIG. 3 is a rear perspective view showing the design for the
three dimensional printer of FIG. 1;

FIG. 4 is a right side perspective view showing the design
for the three dimensional printer of FIG. 1;

FIG. 5 is a front elevational view showing the design for the
three dimensional printer of FIG. 1;

FIG. 6 is a rear elevational view showing the design for the
three dimensional printer of FIG. 1;

FIG. 7 is a left side elevational view showing the design for
the three dimensional printer of FIG. 1;

FIG. 8 is a right side elevational view showing the design for
the three dimensional printer of FIG. 1;

FIG. 9 is a top plan view showing the design for the three
dimensional printer of FIG. 1; and

FIG. 10 is a bottom plan view showing the design for the
three dimensional printer of FIG. 1.

FIG. 11 is a front perspective view of a second embodiment
of a three dimensional printer showing our new design;

FIG. 12 is a left side perspective view showing the design for
the three dimensional printer of FIG. 11;

FIG. 13 is a rear perspective view showing the design for the
three dimensional printer of FIG. 11;

FIG. 14 is a right side perspective view showing the design
for the three dimensional printer of FIG. 11;

FIG. 15 is a front elevational view showing the design for
the three dimensional printer of FIG. 11;

FIG. 16 is a rear elevational view showing the design for the
three dimensional printer of FIG. 11;

FIG. 17 is a left side elevational view showing the design for
the three dimensional printer of FIG. 11;

FIG. 18 is a right side elevational view showing the design
for the three dimensional printer of FIG. 11;

FIG. 19 is a top plan view showing the design for the three
dimensional printer of FIG. 11; and

FIG. 20 is a bottom plan view showing the design for the
three dimensional printer of FIG. 11.

The broken lines in the drawings depict unclaimed environmental
subject matter.
